(57) **CLAIM**

The ornamental design for a slide connector, as shown and described.

DESCRIPTION

FIG. 1 is a perspective view of a left facing slide connector showing the first embodiment of our new design;

FIG. 2 illustrates a front view thereof;

FIG. 3 illustrates a rear view thereof;

FIG. 4 illustrates a top view thereof;

FIG. 5 illustrates a bottom view thereof;

FIG. 6 illustrates a left-side view thereof;

FIG. 7 illustrates a right-side view thereof;

FIG. 8 is a perspective view of a right facing slide connector showing a second embodiment our new design;

FIG. 9 illustrates a front view of FIG. 8;

FIG. 10 illustrates a rear view of FIG. 8;

FIG. 11 illustrates a top view thereof;

FIG. 12 illustrates a bottom view of FIG. 8;

FIG. 13 illustrates a left-side view of FIG. 8; and,

FIG. 14 illustrates a right-side view of FIG. 8.
